MORTISE LOCK

Lorenz Jambrich, South Bend, Ind., assignor of
one-third to Peter Grabner, South Bend, Ind.

Application November 13, 1934, Serial No. 752,870

2 Claims. (Cl. 70—14)

This invention relates to the class of locks and pertains particularly to a key operated mortise lock.

The primary object of the present invention is to provide a key operated lock which is so designed that a certain manipulation of the key in the lock is necessary to effect the actuation of the same, which must be known in order to operate the lock so that an unauthorized person in possession of the key and not knowing the manipulative movements necessary, would not be successful in actuating the lock to disengage the same from a keeper.

A further object of the invention is to provide a lock of the above described character which is of relatively simple design and which is so constructed that a key inserted by a person not knowing the proper manipulation of the same can be freely turned in either direction without giving any hint to the user as to its proper use.

The invention will be best understood from a consideration of the following detailed description taken in connection with the accompanying drawing forming part of this specification, with the understanding, however, that the invention is not confined to any strict conformity with the showing of the drawing but may be changed or modified so long as such changes or modifications mark no material departure from the salient features of the invention as expressed in the appended claims.

In the drawing:

Figure 1 is a vertical sectional view through the lock structure and keeper embodying the present invention, the section being taken substantially upon the line 1—1 of Figure 3.

Figure 2 is a sectional view taken upon the line 2—2 of Figure 1.

Figure 3 is a sectional view taken upon the line 3—3 of Figure 1.

Referring to the drawing, the numeral 1 indicates a portion of a door or other body in which the lock may be mounted while the numeral 2 indicates a portion of a jamb or other structure with which the door or body 1 is associated. While the present lock is designed for use upon any type of closure where one surface is moved toward and into abutting relation with the other, it will be assumed that the present illustration is of a sliding door which has its vertical edge moved toward or away from the face of a jamb.

In the forward face of the door body 1, the usual mortise 3 is formed to receive the lock structure which comprises a housing 4 which is relatively shallow, and which comprises one wall

plate 5 having the side walls 6 integral therewith, and a removable face plate 7 which is brought into abutting relation with the edges of the side walls to close the housing, as illustrated in Figures 2 and 3. One of the side walls of the housing is extended to one side of the casing to form the attaching flange plate 8 which is secured by screws 9 or in any other suitable manner to the edge of the door body in which it is countersunk, as shown in Figure 3.

The wall of the housing of which the plate 8 forms an extension, is provided with an opening 10, through which a keeper yoke 11 extends when the plate 8 is brought into abutting relation with the keeper plate 12' which is countersunk in the face of the jamb 2.

Within the housing 4, the fixed or back wall 5 thereof has secured thereto the pair of aligned guide strips 12 and 13. These strips are in spaced relation and disposed upon opposite sides of the opening 10, as shown in Figure 1, and the strip 13 has a lateral extension or head 14 which constitutes a stop for the purpose hereinafter described.

Disposed against the wall 5 is a bolt plate 15 which at each end has a flange 16 formed thereacross which is provided with a transverse slot 17 to receive the adjacent guide rib 12 or 13. These flanges 16 actually contact the wall 5 to maintain the main body portion of the plate 15 in spaced relation therewith, the opposite side of the body being disposed against the inner face of the cover plate 7, as illustrated in Figures 2 and 3. The edge of the plate 15, which is directed toward the opening 10, is cut away to form the locking bolt 18 which is cut obliquely to form the beveled surface 19 with which the keeper yoke 11 comes into contact when the door is moved to closed position. The point of this bolt 18 normally extends across the opening 10 and is designed to extend through the yoke 11, as shown in Figure 1, to maintain the door locked against movement.

The plate 15 carries a pin 20 on which is swung between the wall 5 and the plate 15, the pointed finger 21 which constitutes a thrust finger in the actuation of the lock. Secured to the inner side wall 6 of the casing is a split annular spring 22, the two ends of which are turned outwardly slightly, as indicated at 23, and are directed toward the inner edge of the bolt plate 15 to receive therebetween the pointed end of the thrust finger 21. Concentrically with this spring 22, there is fixed in the back wall 5 of the housing, a guide pin 24, and the cover plate 7 has a key

hole aperture from which extends inwardly to the opposite wall of the casing, the sleeve 25 which is longitudinally slotted and which is rotatably carried by the cover plate so as to turn 5 with the stem of an inserted key. This sleeve 25 receives the pin 24 in its inner end, as illustrated in Figure 3. The key which is used in association with the present lock comprises a shaft or stem 26 which at its inner end is provided with a socket to receive the pin 24, and 10 extending laterally from this inner end is an arcuate web 27 which adjacent its outer edge has a transverse notch 28 formed therein upon the concave face, and the said outer edge of the 15 key is relatively wide and rounded, as indicated at 29, and the web extends from the key shaft 26 a distance substantially equal to the interior radius of the annular spring 22.

A leaf spring 30 is fixed at one end to a post 20 31 carried upon the wall 5 of the lock housing and has its other end bearing against an end of the lock bar plate 15, as indicated at 32, to constantly urge this plate in a direction to locate the 25 end of the bolt 18 across the opening 10. It will thus be seen that the bolt is constantly in a position to be engaged by the keeper yoke 11 and can only be removed from this position by manipulation of the key.

In the operation of the present lock, when the 30 web of the key is inserted to position within the split annular spring 22, it may be rotated within this spring, and as will be readily apparent, it can be freely turned completely around and as many times as desired, in either direction. In 35 order to properly manipulate the key for the actuation of the lock, it is necessary to turn it in one direction only, in the present instance, in a clockwise direction, to cause the pointed end of the thrust finger 21 to ride over the rounded 40 edge 29 and drop into the groove 28. When this position is reached, the turning of the key in a clockwise direction must be instantly stopped so that the point of the thrust finger will not 45 slip out of the groove 28 and the key reversely rotated so as to force the thrust finger in the direction opposed to the thrust of the spring 30, and thus effect the sliding of the plate 15 and the bolt 18 which forms an integral part thereof 50 in the proper direction to remove the bolt from the yoke 11.

It will be apparent that as soon as the key reaches a certain position in its arcuate path, the pointed end of the thrust finger 21 will slip 55 out of the groove 28 and ride back over the edge

29 and be forced back to its normal position by the closing up of the split annular spring 22 and at the same time, the spring 30 will effect the immediate return of the bolt 18 to its position across the opening 10, so that if the door 5 1 is then closed, the bolt will snap into engagement with the yoke 11 and secure the door.

It will be apparent from the foregoing that in the present lock, the key does not have to be reversely rotated during the unlocking operation 10 in order to disengage it from the thrust finger 21, and also it will be apparent that it can be freely turned in either a clockwise or counter-clockwise direction so that the possibility of a person who has the key without knowing how 15 to properly manipulate it, finding out which is the proper direction to turn the key, is extremely remote.

What is claimed is:—

1. In a lock for use with a key having a stem 20 and a notched web, a sliding bolt, means resiliently urging the bolt to one position for engagement with a keeper, a pointed thrust finger oscillatably connected with the bolt, a split annular spring fixed adjacent to and in the plane 25 of the bolt and having the pointed end of said finger extended thereto between its ends, the ends of the split spring constantly engaging opposite sides of said finger, and means for introducing the key web into the casing comprising 30 a key opening which is concentric with the annular spring.

2. In a lock for use with a key having a stem and notched web, a relatively flat casing having an opening thru one edge wall, a bolt disposed 35 within the casing and having a portion adapted to move across said opening, said bolt having transverse webs extending from one end and having sliding contact with the side wall of the casing, each of said webs having a slot transversely thereof, a rib carried by said side wall of the casing adjacent each web and engaging in the slot thereof, a pointed finger pivotally attached to the bolt upon one side and between said webs and projecting beyond a longitudinal edge 40 of the bolt, an annular spring disposed in the casing adjacent said longitudinal edge of the bolt and in the plane of the bolt, and split transversely to receive the pointed end of said finger, and 45 spring means normally urging said bolt in one direction, said casing having an opening in one side wall concentric with the spring for the reception of said key.

LORENZ JAMBRICH. 55
